UNITED STATES PATENT OFFICE.

WILFORD G. BARTENFELD, OF LORAIN, OHIO.

CHANNEL CONSTRUCTION FOR THE SIDES AND TOPS OF TANKS OF VESSELS.

Application filed August 2, 1927. Serial No. 210,082.

This invention relates to channel construction for the sides and tops of the tanks or the sides and bottoms of the hoppers of vessels, and has for its main object to provide means whereby the sides and tops of the tanks or the sides and bottoms of the hoppers may be constructed of channels in a practical and economical manner. The flanges of the channels not only provide a rigid construction but leakage into the hopper at the rivets as in the usual plate construction is avoided as no rivets enter the hopper.

Another object of the invention is to provide means for properly supporting said side channels and bracing the same.

A further object of the invention is to provide means for rigidly supporting the channels forming the top of the tank or the bottom of the hopper consisting of alternate high floors and beams instead of the usual high floors and longitudinals, thereby reducing weight and saving expense in the substitution of beams for alternate high floors.

With the above and other objects in view as will be clearly understood, the invention will be hereinafter fully described as illustrated in the accompanying drawings, and the novel features thereof will be distinctly pointed out in the appended claims.

In the drawings similar characters of reference indicate corresponding parts.

Figure 1 illustrates the transverse section of the hull of a vessel, taken on line 1-1 of Fig. 3 and looking at one of the high floors, the sides and top of the tank and the sides and bottom of the hopper being constructed in accordance with my invention.

Fig. 2 is a similar view taken on line 2-2 of Fig. 3 and looking at one of the floor beams,

Fig. 3 illustrates a fragmental portion of a plan sectional view taken on line 3-3 of Fig. 1,

Fig. 4 is a similar view taken on line 4-4 of Fig. 1, and

Fig. 5 is a sectional view, on an enlarged scale, taken on line 5-5 of Fig. 2.

Referring to the drawings, the hull of the vessel is of the usual construction consisting of the external side shell 1, the bottom shell 2, the center keelson 3 and the side keelson 4 and intermediate side keel- son 5.

This invention resides in the employment of standard steel channels 6, which are riveted and extend longitudinally of the vessel and are connected together at their flanges by rivets 7, to form the top of the tank and the bottom of the hopper between the side keelsons 4. Also in the employment of standard steel channels 8, which are arranged vertically and inclined, and are connected together at their outwardly extending flanges by rivets 9, to form the inner sides of the side tank and the sides of the hopper. The tank top channels 6 are supported by their downwardly extending flanges resting upon the upper flanged edges 11 of transverse floor plates 12 extending from the center keelson 3 to the intermediate side keelsons 5, and similar flanged plates 13 extend from the intermediate side keelsons 5 to the side keelsons 4. The floor plates 12 and 13 are connected to said keelsons by vertically arranged angle bars indicated by 14, 15 and 16, or in any other suitable manner. Clips, indicated by 17, connect the top channels 6 to the floor plates 12 and 13.

By employing the channel 6 in place of the usual plates to form the tank top, less support for the tank top is necessary, and therefore instead of arranging the floor plates 12 and 13 the usual distance apart, they are spaced twice that distance, and intermediate thereof or substituted for the ones omitted, are arranged beams 18 and 19 formed of channels, the beams 18 extending from the center keelson 3 to the intermediate keelsons 5, and the beams 19 from said intermediate keelsons to the side keelsons 4. Bracket plates 20 connect the inner ends of the beams 18 to the center keelson 3 and support the same from the bottom shell 2, and suitable gusset plates 21 connect the outer ends of said beams to the intermediate keelsons 5. Gusset plates 22 connect one end of the beams 19 to the intermediate keelsons 5, and angle bars 23 and gusset plates 24 connect the other ends of said beams to the side keelsons 4. Arranged between the side keelsons 4 and the external side shell 1 in transverse alignment with the floor plates 12 and 13 and the beams 18 and 19 are vertical plates indicated by 25, and the inner ends of these plates are connected to said side keelsons by vertical angle bars 26. The outer ends of the plates 25 are connected to the lower ends of vertical channels 27. Suit-

able stringers 28 and 29 rest upon and are connected to the upper edges of the vertical plates 25. Gusset plates 30 connect the lower ends of the side tank channels 8 to the vertical floor plates 25 and main deck stringer bracket plates 31 arranged at suitable spaced intervals are connected to the vertical channels 27 at 32 and to the upper ends of said side tank channels at 33. For supporting and strengthening the central portions of the side tank channels 8 against indentation, braces 34 connected to the flanges thereof by gusset plates 35 and to the vertical channels 27 at 36 are provided. The braces 34 are arranged below the plates 31, and stringers 37 and 38 are connected to the upper edges of said braces for strengthening same.

From the drawings and description, it is obvious that there are advantages in constructing the sides and top of the tank and the sides and bottom of the hopper of vessels of channels as disclosed. It will be understood that slight changes in the details of construction may be made within the scope of the claims.

Having fully described my invention what I claim is:

1. In a channel construction for the sides and tops of the tanks of vessels, the combination with channels forming the sides of the tank, of channels forming the top of the tank, floor plates, and the channels forming the top of the tank having their flanges resting upon the floor plates.
2. In a channel construction for the sides and tops of the tanks of vessels, the combination with channels forming the sides of the tank, of channels forming the top of the tank, floor plates, the channels forming the top of the tank having their flanges resting upon the floor plates, and clips fixed to the flanges of the channels forming the top of the tank and said floor plates.
3. In a channel construction for the sides and tops of the tanks of vessels, the combination with channels forming the sides of the tank, of channels forming the top of the tank, floor plates, the floor plates having flanges at their upper edges, and the channels forming the top of the tank having their flanges resting upon the flanged edges of the floor plates.
4. In a channel construction for the sides and tops of the tanks of vessels, the combination with channels forming the sides of the tank, of channels forming the top of the tank, floor plates, beams, the floor plates and the beams being arranged alternately, and the channels forming the top of the tank having their flanges resting upon said floor plates and said beams.
5. In a channel construction for the sides and tops of the tanks of vessels, the combination with channels forming the sides of the tank, of channels forming the top of

the tank, the channels forming the top of the tank being arranged longitudinally, a center keelson, side keelsons, intermediate keelsons between the center keelson and the side keelsons, floor plates connected to the center keelson and to the intermediate keelsons, floor plates connected to the intermediate keelsons and to the side keelsons, and the channels forming the top of the tank having their flanges resting upon said floor plates.

6. In a channel construction for the sides and tops of the tank of vessels, the combination with the channels forming the sides of the tank, of channels forming the top of the tank, the channels forming the top of the tank being arranged longitudinally, a center keelson, side keelsons, intermediate keelsons between the center keelson and the side keelsons, floor plates connected to the center keelson and to the intermediate keelsons, floor plates connected to the intermediate keelsons and to the side keelsons, beams connected to the center keelsons and to the intermediate keelsons, beams connected to the intermediate keelsons and to the side keelsons, said beams being arranged intermediate of said floor plates, and the channels forming the top of the tank having their flanges resting upon said floor plates and said beams.

7. In a channel construction for the sides and tops of the tanks of vessels, the combination with channels forming the sides of the tank, of channels forming the top of the tank, the channels forming the top of the tank being arranged longitudinally, a center keelson, side keelsons, intermediate keelsons between the center keelson and the side keelsons, floor plates connected to the center keelson and to the intermediate keelsons, floor plates connected to the intermediate keelsons and to the side keelsons, bracket plates connected to the center keelson intermediate of said floor plates, beams connected to the bracket plates and to the intermediate keelsons, and beams connected to the intermediate keelsons and to the side keelsons.

8. In a channel construction for the sides and top of the tanks of vessels, the combination of channels arranged vertically and inclined forming the sides of the tank, and channels arranged longitudinally forming the top of the tank.

9. In a channel construction for the sides and top of the tanks of vessels, the combination of channels arranged vertically and inclined forming the sides of the tank, channels arranged longitudinally forming the top of the tank, braces for strengthening the channels forming the sides of the tank, floor plates, and the channels forming the top of the tank having their flanges resting upon said floor plates.

10. In a channel construction for the sides and top of the tanks of vessels, the combination of channels arranged vertically and inclined forming the sides of the tank, channels arranged longitudinally forming the top of the tank, braces arranged horizontally and connected to the flanges of

the channels forming the sides of the tank for strengthening said channels, and stringers fixed to the braces for strengthening 10 the braces.

In testimony whereof I affix my signature.

WILFORD G. BARTENFELD.
